United States Patent Office

Des. 183,000
Patented June 10, 1958

183,000

BOTTLE CARRIER

Irving D. Glazer, Dallas, Tex.

Application October 18, 1957, Serial No. 48,158

Term of patent 14 years

(Cl. D58—5)

Fig. 1.

Fig. 2.

Fig. 3.

Fig. 4.

Fig. 5.

Fig. 1 is a perspective view of a bottle carrier, showing my design;

Fig. 2 is an underside plan view;

Fig. 3 is a top plan view;

Fig. 4 is a side elevational view of the bottle carrier, looking from the direction of the single bottle carrying socket; and

Fig. 5 is a side elevational view looking toward the double socket bottle carrying position.

I claim:

The ornamental design for a bottle carrier, as shown.
